SURGICAL IRRIGATING INSTRUMENT

Filed Sept. 22, 1923

2 Sheets-Sheet 2

UNITED STATES PATENT OFFICE.

LEE F. HERRICK, OF MANSFIELD, OHIO.

SURGICAL IRRIGATING INSTRUMENT.

Application filed September 22, 1923. Serial No. 664,271.

To all whom it may concern:

Be it known that I, LEE F. HERRICK, a citizen of the United States, residing at Mansfield, in the county of Richland and State of Ohio, have invented certain new and useful Improvements in Surgical Irrigating Instruments; and I do hereby declare the following to be a full, clear, and exact description of the invention, such as will enable others skilled in the art to which it appertains to make and use the same.

The invention has for its object the provision of a device for the irrigation of wounds and for administering enemas and douches, and which will enable the flow to be regulated or completely cut off at will, and which includes means for clearing drainage tubes of matter tending to obstruct the same.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application:

Figure 1 is a side elevation of a device embodying the invention,

Figure 2 is a front view thereof,

Figure 3 a rear view,

Figure 4 a vertical, central longitudinal section showing the parts on a larger scale,

Figure 5 is a sectional detail on the line 5-5 of Figure 4,

Figure 6 is a sectional detail on the line 6-6 of Figure 4,

Figure 7 is a side view of an extension tube,

Figure 8 is an end view of a spray nozzle,

Figure 9 is a side view of a curved nozzle,

Figure 10 is a side and end view of a straight nozzle,

Figure 11 is a side and end view of a straight nozzle having an enlarged end in which is formed a single outlet, and

Figure 12 is a side and end view of a straight nozzle having its end enlarged and provided along its sides with rows of openings.

Corresponding and like parts are referred

to in the following description and designated in the several views of the drawings by like reference characters.

The numeral 1 designates the body of a device which is preferably of circular outline and flattened form and which preferably consists of cold rolled copper, nickel-lined and faced. Intersecting openings 2 and 3 are formed in the body 1, the opening 2 extending entirely through the body and the opening 3 terminating a short distance from an edge of the body and extending through the opposite edge and closed by means of a cap 4 threaded thereto and having a central opening through which passes a stem 5. A plug 6 is attached to the inner end of the stem 5 and has a piston fit within the opening 3 and is adapted to occupy a position to obstruct the opening 2 wholly or in part to entirely cut off or regulate the flow of liquid through said opening. A button 7 is provided at the outer end of the stem 5 and is adapted to receive pressure from a digit of the hand when adjusting the plug 6 to regulate or cut off the flow through the opening 2. A helical spring 8 mounted upon the projecting end of the stem 5 and confined between the cap 4 and button 7, normally exerts a pressure to hold the plug 6 at the limit of its outward movement and clear of the opening 2. A spring holder 9 fast to the inner or closed end of the opening 3 projects into the latter and is adapted to enter an opening 10 formed in the inner end of the plug 6 whereby to hold the latter when moved inwardly into closed position, as shown most clearly in Figure 5. The spring holder 9 preferably consists of a split key or pin, the elements of which frictionally engage opposite sides of the opening 10 to hold the plug 6 when pressed inwardly.

A tubular extension 11 projects outwardly from the body 1 in line with the opening 2 and is adapted to have a rubber tube, not shown, fitted thereto. A tubular extension 12 is disposed at the opposite side of the body in line with the opening 2 and its outer end is reduced, as indicated at 13, to admit of the extension tube shown in Figure 7 or any one of the nozzles illustrated being fitted thereto. A finger rest 14 is located adjacent the cap 4 and the edge portion of the body intermediate the tubular

extension 11 and the closed end of the opening 3 is milled or roughened, as indicated at 15, to provide a thumb rest.

A barrel 16 is located opposite the thumb rest 15 and is rearwardly inclined to the opening 2 and is in communication at its inner end with the tubular extension 12. A cap 17 is threaded to the outer end of the barrel 16 and is apertured to receive a stem 18, to the inner end of which is fitted a plunger 19 and to the outer end of which is fitted a button 20. A helical spring 21 is mounted upon the projecting end of the stem 18 and confined between the button 20 and cap 17, normally holds the plunger 19 at the limit of its outward movement. The barrel 16 and plunger 19 constitute elements of a syringe which is utilized to remove matter tending to obstruct drainage tubes.

20 The several forms of nozzles illustrated may be fitted directly to the reduced end 13 of the tubular extension 12, or may be fitted to the extension tube illustrated in Figure 7 when it is required to utilize said tube to enable the nozzle to reach the spot required to be irrigated or treated.

The flow through the opening 2 may be regulated by moving the plug 6 inwardly to a greater or less extent to obstruct said opening to the required degree. The flow may be entirely cut off by pressing the plug 6 inwardly, as indicated in Figure 5, said plug being maintained in closed position by the spring holder 9. When the opening 2 is thus completely obstructed, the plunger 19 may be operated to remove any obstruction in a drain tube by forcing a portion of the liquid therethrough. The plug 6 is provided with a vent passage 22 for the escape of any liquid finding its way into the inner portion of the opening 3 to admit of the closing of the opening 2 when the plug is pressed inwardly. The passage 22 may consist of a groove or channel formed in a side 45 of the plug.

What is claimed is:

1. A device of the character specified, comprising a body having intersecting openings, the one providing for the flow of a liquid therethrough, and a plug movable in the other opening for cutting off or regulating the flow of said liquid, said plug having an opening in its inner end, and a spring holder adapted to enter the opening of the plug and engage the same frictionally to hold the plug in the required adjusted position.

2. A device of the character specified, comprising a body provided with intersecting openings and having tubular extensions in

line with and at opposite ends of one of the openings, the other opening being closed at its inner end, a spring actuated plug within the last mentioned opening and adapted to control the first mentioned opening and having an opening at its inner end, and a spring holder within the closed end of the opening and adapted to frictionally engage the opening of the plug and hold the latter in the required adjusted position.

3. A device of the character specified, comprising a body provided with intersecting openings, a plug within one of the openings and adapted to be projected across the intersection of the opening to control the other opening, and a syringe mounted upon the body and in communication with the controllable opening and adapted to remove obstructing matter from a drainage tube.

4. A device of the character specified, comprising a flat body of approximately circular outline and having intersecting openings, the one extending through opposite edges of the body and having tubular extensions in line therewith, and the other opening being closed at its inner end, a plug having a piston fit within the last mentioned opening and adapted to control the extended opening, a spring normally urging the plug outwardly, a holder adapted to engage the plug and hold the same when pressed inwardly, and a syringe mounted upon the body and in communication with one of said tubular extensions and adapted to remove obstructing matter from a drainage tube.

5. A device of the character specified, comprising a flat body of approximately circular outline having intersecting openings, one of the openings being closed at its inner end and the other opening extending through opposite edges of the body and having tubular extensions in line therewith, an edge portion of the body being roughened to provide a thumb rest which is disposed at one side of a tubular extension, and said body having a finger rest at the opposite side of said tubular extension, a spring actuated plug within the opening closed at one end, a holder for retaining the plug in the required adjusted position, and a syringe mounted upon the body in an inclined position and in communication with the tubular extension opposite that disposed between the thumb and finger rests.

In testimony whereof I affix my signature in presence of two witnesses.

LEE F. HERRICK.
